(57) **CLAIM**

The ornamental design for a golf divot repair tool, as shown and described.

DESCRIPTION

FIG. 1 is a rear perspective view of a golf divot repair tool, according to the inventor;

FIG. 2 is a front perspective view thereof;

FIG. 3 is a rear view thereof;

FIG. 4 is a front view thereof;

FIG. 5 is a right view thereof with the left view being a mirror image thereof;

FIG. 6 is a top view thereof; and,

FIG. 7 is a bottom view thereof.

The broken lines shown in the Figures are for environmental purposes only and form no part of the claimed invention.
